CIRCULAR SAW

Melvin H. Boldt, Glenview, Ill., assignor to G. W.
Murphy Industries, Inc., Houston, Tex.

Filed Nov. 16, 1970, Ser. No. 25,993

Term of patent 14 years

Int. Cl. D8—03

U.S. Cl. D8—66

Fig.-1

Fig.-2

Fig- 3

Fig- 4

FIG. 1 is a top plan view of a circular saw, showing my new design;

FIG. 2 is a left side elevational view of the circular saw illustrated in FIG. 1;

FIG. 3 is a right side elevational view of the circular saw illustrated in FIG. 1;

FIG. 4 is a bottom plan view of the circular saw illustrated in FIG. 1;

FIG. 5 is a perspective view of the circular saw illustrated in FIG. 1;

FIG. 6 is a front elevational view of the circular saw illustrated in FIG. 1; and

FIG. 7 is a rear elevational view of the circular saw illustrated in FIG. 1.

The broken line showing of a saw blade is for illustrative purposes only.

I claim:

The ornamental design for a circular saw, as shown and described.
